SEWING MACHINE CARRYING CASE OR SIMILAR ARTICLE

Monte L. Levin, Roslyn, N.Y., assignor to The Singer
Manufacturing Company, Elizabeth, N.J., a corporation of New Jersey

Filed Jan. 30, 1959, Ser. No. 54,399

Term of patent 14 years

(Cl. D87—5)

Fig.1.

Fig.4.

Fig.5.

Fig.6.

Fig.3.

Fig.2.

Fig.7.

Fig. 1 is a perspective view of a sewing machine carrying case or similar article showing my new design,

Fig. 2 is a reduced scale front elevational view

Fig. 3 is a reduced scale left side elevational view

Fig. 4 is a reduced scale rear elevational view

Fig. 5 is a reduced scale right side elevational view

Fig. 6 is a reduced scale top plan view and

Fig. 7 is a reduced scale bottom plan view.

The essential features of my design reside in the portions shown in full lines.

I claim:

The ornamental design for a sewing machine carrying case or similar article, substantially as shown and described.
